(57) **CLAIM**

The ornamental design for a fluid delivery device user interface, as shown and described.

DESCRIPTION

FIG. 1 is a front perspective view of a fluid delivery device user interface showing my new design;

FIG. 2 is a front elevational view showing the design for the fluid delivery device user interface of FIG. 1;

FIG. 3 is a left side elevational view showing the design for the fluid delivery device user interface of FIG. 1;

FIG. 4 is a right side elevational view showing the design for the fluid delivery device user interface of FIG. 1;

FIG. 5 is a top plan view showing the design for the fluid delivery device user interface of FIG. 1; and,

FIG. 6 is a bottom plan view showing the design for the fluid delivery device user interface of FIG. 1.

The broken lines shown in the drawings illustrate portions of the fluid delivery device that form no part of the claimed design.
